CLAIM

The ornamental design for an billiard table, as shown and described.

DESCRIPTION

FIG. 1 is a first perspective view showing the first, second and third sides of an billiard table.

FIG. 2 is a second perspective view showing the second, third and fourth sides of the billiard table of FIG. 1.

FIG. 3 is a third perspective view showing the third, fourth and fifth sides of the billiard table of FIG. 1.

FIG. 4 is a fourth perspective view showing the fourth, fifth and sixth sides of the billiard table of FIG. 1.

FIG. 5 is a fifth perspective view showing the fourth, fifth and sixth sides of the billiard table of FIG. 1.

FIG. 6 is a sixth perspective view showing the fifth, sixth and seventh sides of the billiard table of FIG. 1.

FIG. 7 is a seventh perspective view showing the sixth, seventh and eighth sides of the billiard table of FIG. 1.

FIG. 8 is an eighth perspective view showing the seventh, eighth and first sides of the billiard table of FIG. 1.

FIG. 9 is a ninth perspective view showing seventh, eighth and first sides of the billiard table of FIG. 1.

FIG. 10 is a perspective view showing the underside of the billiard table of FIG. 1.

FIG. 11 is a top view of the billiard table of FIG. 1 with an optional cover attached; and,

FIG. 12 is a perspective view of the billiard table of FIG. 1 with an optional ball rack on the playing surface.

1 Claim, 12 Drawing Sheets
